Primary Examiner — Lauren D McVey(74) *Attorney, Agent, or Firm* — ScienBiziP, P.C.(57) **CLAIM**

The ornamental design for a label printer, as shown and described.

DESCRIPTION

FIG. 1 is a front, right, and top perspective view of a label printer, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a partial enlarged view of the area labeled 9 in FIG. 1 in order to show aspects of the design not otherwise apparent.

The broken lines shown in the drawings are included for the purpose of illustrating portions of the label printer that form no part of the claimed design. The dot-dash broken lines indicating an enlargement portion of the design form no part of the claimed design.
